UNITED STATES PATENT OFFICE.

FRED HIRSH, OF NEW YORK, N. Y., ASSIGNOR TO THE ADJUSTA COMPANY, INC., OF NEW YORK, N. Y., A CORPORATION OF NEW YORK.

FASTENER.

Application filed July 18, 1923. Serial No. 652,313.

To all whom it may concern:

Be it known that I, FRED HIRSH, a citizen of the United States, residing in the city of New York, county and State of New York, have invented certain new and useful Improvements in Fasteners, of which the following is a specification.

My present invention relates to a fastener, and more particularly to a slotted metallic plate or slide which at the back is provided with an integral hook whereby, in co-operation with an eyelet, loop, or other complementary member, a strap may be adjustably and detachably connected to another part of the same strap or to a different strap or article.

The object thereof is to provide a one-piece, slidably adjustable hook member which is neat and attractive in appearance, which may be cheaply made, and which is efficient for the purpose in view and will not readily become detached.

The invention will be understood by reference to the accompanying drawing, where-

25 in—

Fig. 1 is a front or plan view showing a strap equipped with my improved fastening member and thereby attached to a second strap; Fig. 2 is a perspective view of the parts separated, showing the back of the fastener; Fig. 3 is a longitudinal section through the fastener by itself and through the upper or back strap and the eyelet set therein; Fig. 4 is a perspective view of the back of a modified form of the fastener and of the end of a strap provided with a loop for co-operation with the hook of the fastener; and Fig. 5 is a view of this last fastener in longitudinal section.

40 As illustrated in Figs. 1-3, 6 indicates a double strap or tab, depending from a garment, in the outer fold of which is set an eyelet 7, and 8 indicates the end of a second strap—that of a hose-supporter, for example—upon which the fastener 9 is mounted. The fastener proper, stamped out and shaped up from a thin sheet of metal, consists of a body or slide, provided with two transverse slots and the resulting three bars, 45 which is upset to form a stiffening flange 10 along both sides and across each end, and of a hook 11, integral with the intermediate or middle bar, which hooks into the eyelet. One feature of the hook is that it is formed 50 in part from the material cut from one of

the slots and in part from the middle bar by cutting back therein on either side of the hook, thus enabling me to provide a hook of suitable length in a body of small size and with a minimum of material. Another 60 feature of the hook is that from its base on the middle bar it is bent on somewhat curved lines first back slightly beyond the perpendicular and then forward into a plane substantially parallel to the plane of the 65 body, thus forming at its back a re-entrant angle or concavity 12, adapted to receive the inner edge of the eyelet, and a convexity or rounded hump 13 which by engaging the back of the eyelet serves as a means for 70 largely preventing any accidental separation of the hook from the eyelet. The hook is also upset, near its outer end, to provide a slight forward projection 14 which further serves to lock it within the eyelet and so to 75 prevent the accidental disengagement of the parts.

This fastener is equally adapted, its position being reversed, for the attachment of the shoulder strap to a corner of the bib of 80 a child's overalls, or it may be used in any connection or for any purpose desired.

The form of fastener 9^a shown in Figs. 4 and 5 is designed especially for use on galoshes, or for fastening the straps of 85 ladies' low shoes and slippers, either in co-operation with an eyelet or with a metallic or other loop 7^a. Here the stiffening flanges are turned forwardly, the outwardly curved side flanges 10^a forming with the body a 90 channel of a depth to receive the strap, while the transverse flanges 10^b, integral with the sides of the middle bar, serve in connection with the slots to prevent the slipping of the strap. The hook 11^a is formed wholly with- 95 in the middle bar, which is wide enough for the purpose, and is provided with the locking projection 14^a which is usually found sufficient to prevent the accidental disengagement of the hook from a loop; hence, 100 when the fastener is to be used in co-operation with a loop, the rounded hump at the back of the hook may if desired be omitted.

What I claim as new, and desire to secure by Letters Patent, is—

1. A one-piece metallic fastener comprising a slotted body or slide which is upset to provide longitudinal and transverse stiffening flanges and a hook which is integral with an inner bar of the body and is formed in 110

part at least from the material of the bar.

2. A one-piece metallic fastener comprising a body, pierced to provide two transverse slots and three bars, which is flanged along both sides and across each end, and a hook, integral with the middle bar, which is formed partly from the material cut from one slot and partly from the bar.

3. A one-piece metallic fastener comprising a body, pierced to provide two transverse slots and three bars which is stiffened by flanges along its sides and transversely along the sides of the middle bar and a hook which is integral with the middle bar.

4. A one-piece metallic fastener comprising a transversely slotted body, adapted to be adjustably mounted upon a strap, and a hook which is integral with an inner bar of the body and which from its base on the bar is bent outwardly slightly beyond the perpendicular and then back into a plane substantially parallel to the plane of the body, forming at the back of the hook a re-entrant angle adapted to receive an edge of a co-operating member like an eyelet and so to render unlikely the accidental displacement of the hook.

5. A one-piece metallic fastener comprising a slotted body and integral therewith a hook which, as providing double means for rendering unlikely its accidental disengagement from a co-operating member, from its base on the body is bent on somewhat curved lines first outwardly slightly beyond the perpendicular and then back into a plane substantially parallel to the plane of the body and near its outer end is upset to form a slight inwardly extending locking projection.

6. A one-piece metallic fastener comprising a slotted body or slide which is upset to provide longitudinal and transverse stiffening flanges and a hook which is integral with an inner bar of the body and is formed in part at least from the material of the bar by being bent first outwardly slightly beyond the perpendicular and then back into a plane substantially parallel to the plane of the body.

7. A one-piece metallic fastener comprising a body, pierced to provide two trans-

verse slots and three bars, and an integral hook which is formed in part from the material cut from one slot and in part from the transverse bar and which is so shaped as to provide means rendering unlikely its accidental disengagement from a co-operating member.

8. A one-piece metallic fastener comprising a body, pierced to provide two transverse slots and three bars, which has on its front outer face stiffening flanges along both sides and transversely along the sides of the middle bar and at its back has a hook integral with the middle bar and provided with means rendering unlikely its accidental disengagement from a co-operating member.

9. A one-piece metallic fastener comprising a body, pierced to provide a plurality of transverse slots and bars, which is stiffened along both sides by flanges upset outwardly from its front face and at its back has a hook which is integral with an intermediate bar and is formed in part at least from the material thereof.

10. A one-piece metallic fastener comprising a body, pierced to provide a plurality of transverse slots and bars, which is stiffened on both sides by flanges upset outwardly from its front face and at its back has a hook which is integral with an intermediate bar and is provided with means rendering unlikely its accidental disengagement from a co-operating member.

11. A one-piece metallic fastener comprising a body, pierced to provide a plurality of transverse slots and bars, which is channeled on its front face by convexly-curved outwardly projecting flanges on both sides and at its back is provided with a hook which is integral with one of the transverse bars.

12. A one-piece metallic fastener comprising a body, pierced to provide a plurality of transverse slots and bars, which is channeled on its front face by outwardly projecting flanges on both sides and at the back is provided with a hook which is integral with an intermediate transverse bar and has its base located at a point intermediate the two sides of the bar.

FRED HIRSH.
